UNITED STATES PATENT OFFICE

WILHELM SCHLEIFER, OF VIENNA, AUSTRIA

TAB FOR REGISTRATION CARDS OR THE LIKE

Application filed May 31, 1930, Serial No. 458,831, and in Austria June 3, 1929.

This invention relates to improvements in tabs which consist of a frame provided with a window and with three bent ears, the two outside ears serving for threading through 5 slots of a file or card to secure the tab to the same, while the middle ear forms the back-wall of the window.

One mode of carrying out the present invention is illustrated by way of example on 10 the accompanying sheet of drawings in which:—

Fig. 1 shows a tab fitted to a card.

Figs. 2 and 3 are sectional views, the sections being taken on lines 2—2 and 3—3 15 respectively of Fig. 1.

Fig. 4 is a view of the blank for the tab cut or stamped from a sheet of suitable material.

The tab consists of a frame *a* and ears *b*, *c* 20 and *d* extending outwardly from the lower side of the frame. The outside ears *b* and *d*, after having been bent into a position substantially parallel to the plane of the frame *a*, form clamping members, which are 25 threaded through slots *e* formed in pairs adjacent an edge of a registration card *f*, and thereby not only secure the tab to the latter but also prevent its lateral displacement. The ends of the ears *b* and *d* extend 30 up behind the body of the tab and the window, as shown clearly in Figure 1. The ear *c*, disposed between the said outside ears, is bent rearwardly and upwardly to form a back-wall for the window, the bend at the 35 bottom of the said upturned ear *c* being adapted to rest on the edge of the registration card in order to prevent the inward sliding of the tab. The side edges *g* of the 40 frame are flanged rearwardly in order to prevent any lateral movement of the index slips or labels when inserted in the tab. The 45 said index slips or the like rest on the bent part of the middle ear *c* and thus cannot move downward, while the upper cross-bar of the frame prevents an unintentional removal of the index slip when handling the registration card.

Thus an essential feature of the present 50 invention consists in that not only the tab

but also the index slip behind the window are retained in desired position and also the adjacent registration cards cannot be entangled with one another.

I claim:—

1. Tab for use in connection with registration cards or the like, comprising in combination, a frame, and a number of ears at one edge of said frame, said ears adapted to be bent to lie in planes substantially parallel to the plane of said frame, the outside ears being adapted to be threaded through slots of the registration card, while the ear disposed between the outside ears forms the back-wall of the window in said frame.

2. Tab for use in connection with registration cards or the like, comprising in combination a frame, and three ears at one edge of said frame, said ears adapted to be bent to lie in planes substantially parallel to the plane of said frame, the two outside ears being adapted to be threaded through slots of the registration card, while the middle ear forms the back-wall of the window in 70 said frame.

3. Tab for use in connection with registration cards or the like, comprising in combination a frame, and three ears at one edge of said frame, said ears adapted to be bent to lie in planes substantially parallel to the plane of said frame, the two outside ears being adapted to be threaded through slots of the registration card, while the middle ear forms the back-wall of the window in 80 said frame and rests on the edge of said card.

4. Tab for use in connection with registration cards or the like, comprising in combination a frame with the lateral edges turned off, and three ears at one edge of 90 said frame, said ears adapted to be bent to lie in planes substantially parallel to the plane of said frame, the two outside ears being adapted to be threaded through slots of the registration card, while the middle 95 ear forms the back-wall of the window in said frame.

In testimony whereof I affix my signature.

WILHELM SCHLEIFER.
